UNITED STATES PATENT OFFICE

CHARLES HARRIS, OF FRANKFORT, KENTUCKY, ASSIGNOR TO AMERICAN IDENTIFICATION COMPANY, OF WINCHESTER, KENTUCKY, A CORPORATION OF DELAWARE

KEY CHART

Application filed September 13, 1926, Serial No. 135,132. Renewed June 20, 1930.

This invention relates to the issuance of checks and to the identification generally of articles, persons, etc., and has for its object to provide a key chart by means of which checks may be so marked that if altered in any material way such alteration may be readily detected; and by means of which any article or person having a predetermined number, may be accurately identified.

Other objects and advantages of the invention will be apparent from the following description when taken in connection with the accompanying drawings; in which

Figure 1 is a plan view of a key chart for use in the present invention.

Figure 2 is a plan view of a locator to be used in connection with the chart.

Figure 3 is a plan view of a check perforated in accordance with the present invention.

Referring to the drawings in greater detail the numeral 1 indicates a key chart which is ruled to provide a plurality of blocks or squares 2 in which are arbitrarily arranged a plurality of numbers. These numbers though arbitrarily arranged are so placed that in each consecutive ten blocks lengthwise of the chart all of the numbers from 0 to 9 appear. The chart is also provided with co-ordinates 3 and 4. The co-ordinates 3 in the present form of chart representing the days of the month from 1 to 31 and the co-ordinates 4 may consist of the alphabet, and other markings may also be used such as "Local", "State", etc.

In the use of the key chart as will be hereinafter described, a locator is necessary and this locator which is designated by the numeral 5 comprises a rectangular member provided with a central rectangular opening of a length equivalent to ten blocks lengthwise of the chart and five blocks in the vertical direction of the chart. Two of the sides of the locator are marked off into ten sections and are numbered 1, 2, 3, 4, 5, 6, 7, 8, 9, 0, while the shorter sides of the locator are divided off into five blocks or sections which are designated hundredths, tenths, units, tens, hundreds; these shorter sides of the locator may, of course, be made longer

and divided off into thousands, tens of thousands, etc., is desired.

In the operation of the device we will assume that a check is to be made out to Lawrence Fry on January 20, 1926 for \$518.63. In practicing the invention the locator 5 will be placed on the master chart as indicated by heavy dot and dash lines; the vertical position thereof being determined by the day of the month, which is the 20th, and the horizontal position by the first letter of the surname of the payee, which is F. The upper left hand corner of the opening in the locator 5 is positioned at the point where the imaginary lines through the co-ordinates F and 20 meet. It will be understood, however, that should the day of the month be such as to bring a portion of the locator below the bottom of the key chart it will be necessary to fix the position of the locator by the lower left hand corner thereof instead of by the upper left hand corner. With the locator positioned as indicated in heavy dot and dash lines in Figure 1 and the check being placed in any suitable type of punching machine, the operator will read off in that section of the key chart which is surrounded by the locator the amount of the check and will then depress the keys in the punching mechanism corresponding to the positions in the selected portion of the key chart. In the present instance, \$518.63, is the amount of the check and these numbers are indicated on the selected section of the chart by dot and dash circles around the figures, and while here shown as extending in a straight line across the selected area, it will be understood that this number was selected to simplify matters and that the numbers will not always extend in a straight line on the chart or on the check. After the check has been punched as indicated and if it is desired to afford further protection so as to eliminate the possibility of the payee's name being changed on the check, an identification number is given to the payee and this number may be determined in several ways. In the present instance, we have shown the identification number as determined by the 100

third letter of the given name of the payee which is W. Therefore the locator will be moved to the right of the chart as indicated in lighter dot and dash lines so that the 5 imaginary line through the W, the third letter of the payee's given name, and the imaginary line through the 20, the day of the month, will intersect in the upper left hand corner of the locator. Then taking 10 the number in the new selected area in the same relative positions as in the first selected area and totaling them the amount will be 26 and this will be the identification 15 number of the payee. Or, the identification number might be provided by merely taking down the figures as they occur in the new position on the chart; the identification number in the example would then be 36,557. Of course, this identification number 20 could be determined in many different ways; for instance, the first letter of the given name of the payee might be used, or anyone of the letters of the surname might 25 also be used. The particular manner of locating the section of the chart to be used for identification purposes will, of course, be predetermined by the parties using the chart and also the co-ordinates to be used for locating the section of the chart for 30 use in punching or otherwise indicating the amount of the check may be different from those herein shown and described. For instance, the months themselves might be used instead of days of the month. In other 35 words, almost any variety of co-ordinates might be used, it only being necessary that the co-ordinates be predetermined as between the parties using the system.

The above description relates merely to a 40 single use of the key chart disclosed herein, but it is to be distinctly understood that the chart is susceptible of various alterations of the style and positions of co-ordinates, as well as the arrangements of the 45 figures, it being essential only that a series of rows of figures be provided in which each row includes the numbers 0 to 9, that the number of rows be sufficient to permit of shifting the locator to varying positions, and 50 that means be provided for determining the positions selected.

From the foregoing description taken in connection with the accompanying drawings it will be observed that I have devised a 55 relatively simple method by which checks may be marked in cipher to prevent fraudulent alteration thereof as to the amount and which will provide identification numbers so as to prevent an alteration of the 60 payee's name; and that the method devised is such as to provide for an endless number of combinations which may be varied at will as predetermined between parties using the 65 system.

65 In accordance with the patent statutes I

have described what I now believe to be the best embodiment of the invention; but I do not wish to be understood thereby as limiting myself or the scope of the invention, as many changes and modifications 70 may be made without departing from the spirit of the invention; all such I aim to include in the scope of the appended claims.

What I claim as new and desire to secure by Letters Patent is:

1. In a device of the class described, a key chart comprising a body portion having a plurality of horizontal and vertical rows of figures, one of said plurality of rows of figures having the numerals 0 to 9 recurring at intervals, indicia extending along one edge of the block of figures for use in determining the section of the chart to be used, and a locator comprising a substantially rectangular sheet of material provided with an opening and markings on said sheet spaced to correspond with the spacing of the figures on the chart.

2. In a device of the class described, a key chart comprising a body portion having a plurality of horizontal and vertical rows of figures, one of said plurality of rows of figures having the numerals 0 to 9 recurring at intervals, indicia extending along one edge of the block of figures for use in determining the section of the chart to be used, and a locator comprising a substantially rectangular sheet of material provided with indicating means spaced to correspond with the spacing of the figures on the chart.

3. In a device of the class described, a key chart comprising a body portion having a plurality of horizontal and vertical rows of figures, one of said plurality of rows of figures having the numerals 0 to 9 recurring at intervals, coordinates along the edges of the chart, and a locator comprising a substantially rectangular sheet of material provided with indicating means spaced to correspond with the spacing of the figures on the chart.

CHARLES HARRIS.
